(57) **CLAIM**

I claim the ornamental design for the skull hookah pipe, as shown and described.

DESCRIPTION

FIG. 1 is a front view of the skull hookah pipe;

FIG. 2 is a right perspective view of the skull hookah pipe;

FIG. 3 is a left perspective view of the skull hookah pipe;

FIG. 4 is a left side view of the skull hookah pipe;

FIG. 5 is a back view of the skull hookah pipe;

FIG. 6 is a right side view of the skull hookah pipe;

FIG. 7 is a front view of the stem portion of the skull hookah pipe;

FIG. 8 is a right side view of the stem portion of the skull hookah pipe;

FIG. 9 is a left perspective view of the stem portion of the skull hookah pipe; and,

FIG. 10 is a back view of the stem portion of the skull hookah pipe.

One of the mouthpiece elements of the design has been removed in FIGS. 6, 8, and 9 for convenience of illustration.
